UNITED STATES PATENT OFFICE.

WALTER J. McCOY, OF SOUTH OMAHA, NEBRASKA.

TRUCK.

1,027,557.

Specification of Letters Patent.

Patented May 28, 1912.

Application filed July 12, 1911. Serial No. 638,082.

To all whom it may concern:

Be it known that I, WALTER J. McCoy, a citizen of the United States, residing at South Omaha, in the county of Douglas and 5 State of Nebraska, have invented new and useful Improvements in Trucks, of which the following is a specification.

The present invention relates to improvements in trucks for handling boxes, and it 10 has especial reference to box-trucks of the general type shown and described in my prior Patent No. 993,265.

A structural embodiment of the invention is illustrated in the accompanying drawings, 15 whereof—

Figure 1 is a perspective view of the improved truck, Fig. 2 is a side elevation thereof, said figures showing the lever-operated slide in forward position. Fig. 3 is a plan view of said slide, Fig. 4 is a perspective view of the clip connected to the slide, Fig. 5 is a fragmental side elevation of the truck, showing the slide in retracted position, Figs. 6 and 7 are detail views, of a pair 20 of pallets which are employed when the truck is used for handling bricks.

Referring to said drawings, 1 designates the square axle of the truck, 2 the wheels which are rotatably fitted on the trunnions 30 3 on the axle ends, and 4 the truck frame. Said frame comprises a pair of inclined side beams 5 connected at their upper or rear ends by a cross-bar 6, and adjacent their lower or front ends to the axle, a pair of rearward extensions 7 which are formed upon the lower ends of the side beams 5, and, in turn, have the handles 8 fastened thereto, and a pair of vertical supports or legs 9. Legs 9 are fastened at their upper ends to beams 5 35 and their lower ends are joined together by a cross-bar 10, the first-mentioned leg ends being attached to said beams at the same point as the front ends of a pair of braces 11 whose rear ends terminate in eyes or 40 collars 12 that are fastened to said handles.

To the upper ends of beams 5 is hinged a load-supporting platform 13 which, in the present instance, consists of a pair of spaced longitudinal sills 14 connected together at 45 intervals by cross-pieces 15, said sills being provided adjacent their upper ends with eyes 16 through which the cross-bar 6 passes. The lower portions of these sills are provided with L-shaped brackets 17 that are 50 connected with the adjacent cushioning devices 18, said devices being identical in con-

struction with the corresponding parts or elements present in my prior application above identified, for which reason they require no description beyond the fact that 60 they include upper and lower plates 19 and 20, and a series of interposed springs 21, the lower plates 20 being connected with the axle.

Adjacent the wheels, and between the latter and the ends of the beam 5, the axle carries a pair of boxings 22 which are rigidly secured thereto by plates 23 held in place in any suitable manner. These boxes are provided, in addition to the openings 70 through which the axle ends pass, with transverse passages 24 designed to loosely receive the offset upper ends of a pair of 75 upstanding arms 25 secured to the rear ends of tongues 26. Said tongues are slidably received in grooved guides 27 fixed upon the ends of the cross-piece 28 of a fork 29, the cross-piece having also affixed to its central portion a lug 30. To this lug is pivoted the lower end of a link 31, composed of a pair 80 of counterpart spaced members 32 which diverge toward their lower ends, said members having their upper ends introduced between and pivoted to the lower ends of a pair of spaced arcuate links 33, whose upper 85 ends are pivoted between the apices of a pair of angular brackets 34 arranged in spaced parallel relation to each other and connected at their rear or upper ends to the central portion of the cross-bar 10. 90

Between the upper portions of the link members 32 is fixed a depending arm 35 to which is connected the forked lower end of the operating lever 36, said lever being provided adjacent its upper end with a series of notches or teeth 37 designed to engage cross-bar 10, and at said end with a handle 38. 95

The lower ends of the sills 14 are provided with L-shaped lifting plates 39, but these are omitted when the truck is used for handling brick, in which instance the two pallets 40 and 41 shown in Figs. 6 and 7 are employed. The first of these pallets replaces the sliding fork and is provided with a central lug 42 and with guides 43 100 which are identical with the corresponding elements on said fork. The second, or auxiliary pallet 41 is adapted to be carried by the platform 13, and is constructed of adjustably connected parts, so as to enable it 105 to be fitted to platforms of different widths; the aforesaid adjustable parts consist, in 110

the present instance, of a plate or body 44 to whose opposite sides are attached a pair of laterally-flanged or angular members 45 which are formed with slots 46, screw bolts 5 or other suitable fastening devices 47 being passed through said slots and through registering openings in the body 44 to retain said members in adjusted position.

The operation when handling boxes, is 10 substantially as follows:—The truck is wheeled close enough to the box to enable the sharpened feet of the lifting plates to be inserted beneath the bottom of the box, the truck having previously been shifted or 15 tilted to bring the supporting platform into vertical position. The handles are then swung slightly backward to raise up the end of the box engaged by the lifting plates and the lever 36 then forced downward and 20 forward, to move the sliding fork beneath the box. This movement of the lever forces 25 the link 31 and, in consequence, the fork to move forward, as will be understood, and has the further effect of swinging the curved links 33 in the same direction, said lever moving from the position shown in Fig. 5 to that shown in Figs. 1 and 2, in which latter position one of its teeth or notches 37 is engaged by the cross-bar 10, thus locking 30 the lever in place. To withdraw the fork it is only necessary to exert an upward pull upon the lever, whereupon a reverse movement of the latter and of the parts 31 and 33 will take place, such movement being 35 preferably terminated by the contact of the parts 33 with a suitable stop, as, for example, a cross-pin 48 carried by the brackets 34. Practically the same operation takes place when the truck is used for handling 40 brick, the pallets 40 and 41 being employed as above stated.

With reference to the passages 24, through 45 which the offset ends of the arms 25 extend, it may be stated that these passages are sufficiently wide to permit play of said ends forward and backward bodily therein, side- 50 wise play being, however, prevented. This play is necessary in order to enable the fork 29, to remain flat upon the ground until the end of the box has been raised high enough to permit said fork to be forced thereunder without interference on the part 55 of the box end.

What is claimed is:

55 1. In a tiltable truck, the combination of a wheeled frame, a load-supporting platform hinged thereto, a movable device co-operating with said platform for raising the load when the truck is tilted, a link connected to said device, a pair of swinging links to which the first-named link is pivoted, a support to which the second-named links are pivoted, and a lever connected to said first-named link for operating 60 said device.

2. In a tiltable truck, the combination of a wheeled frame, a load-supporting platform hinged thereto, a movable device co-operating with said platform for raising the load when the truck is tilted, a link connected to said device, a pair of swinging links to which the first-named link is pivoted, a support to which the second-named links are pivoted, a lever connected to said first-named link for operating said device, and means carried by said support and adapted for engagement by said second-named links during their swinging movement in one direction, for limiting such movement. 70

3. In a tiltable truck, the combination of a wheeled frame including an axle, a load-supporting platform hinged to said frame, a movable device co-operating with said platform for raising the load when the truck is tilted, a link pivoted at one end to said device and provided intermediate its ends with a depending arm, an angular member having one end connected to said axle, and the other end to said frame, a curved member pivoted 80 at one end to the apex of said angular member and at its opposite end to the other end of said link, and an operating lever for said device having one end pivoted to said arm. 90

4. In a tiltable truck, the combination of a wheeled frame including an axle, a load-supporting platform hinged to said frame, a movable device co-operating with said platform for raising the load when the truck is tilted, a link pivoted at one end to said device and provided intermediate its ends with a depending arm, an angular member having one end connected to said axle, and the other end to said frame, a curved member pivoted at one end to the apex of said angular member and at its opposite end to the other end of said link, an operating member for swinging said curved member and shifting said device having one end pivoted to said arm, and means carried by said angular member and adapted for engagement by said curved member during the swinging movement of the latter in one direction, for limiting such movement. 100

5. In a tiltable truck, the combination of a wheeled frame including an axle, a load-supporting platform hinged to said frame, a movable device co-operating with said platform for raising the load when the truck is tilted, said device being provided with a plurality of guides, a plurality of boxes attached to said axle, a separate tongue slidably engaged with each guide and connected with a box, and means for operating said device. 110

6. In a tiltable truck, the combination of a wheeled frame including an axle, a load-supporting platform hinged to said frame, a movable device co-operating with said platform for raising the load when the truck 120 130

is tilted, said device being provided with a plurality of guides, a plurality of boxes attached to said axle, and provided each with a transverse passage, a tongue slidably engaged with each guide and provided with an upstanding arm fitted at its upper end in the passage in the adjacent box, and means for operating said device.

7. In a tilttable truck, the combination of a wheeled frame including an axle, a load-supporting platform hinged to said frame, a movable device coöperating with said platform for raising the load when the truck is tilted, said device being provided with a plurality of guides, a plurality of boxes attached to said axle, a separate tongue slidably engaged with each guide and connected with a box, a link connected to said device, and a lever connected to said link for operating said device.

8. In a tilttable truck, the combination of a wheeled frame including an axle, a load-supporting platform hinged to said frame, a movable device coöperating with said platform for raising the load when the truck is tilted, said device being provided with a plurality of guides, a plurality of boxes attached to said axle, a separate tongue slid-

ably engaged with each guide and connected with a box, a link connected to said device, 30 a pair of swinging links to which the first-named link is pivoted, a support to which the second-named links are pivoted, and a lever connected to said first-named link for operating said device.

9. In a tilttable truck, the combination of a wheeled frame including an axle, a load-supporting platform hinged to said frame, a movable device coöperating with said platform for raising the load when the truck is 40 tilted, said device being provided with a plurality of guides, a plurality of boxes attached to said axle, and provided each with a transverse passage, a tongue slidably engaged with each guide and provided with 45 an upstanding arm fitted at its upper end in the passage in the adjacent box, a link connected to said device, and a lever connected to said link for operating said device.

In testimony whereof I have hereunto set 50 my hand in presence of two subscribing witnesses.

WALTER J. McCOY.
